UNITED STATES PATENT OFFICE

JAMES R. HUGHES, OF SOUTH BEND, INDIANA, ASSIGNOR TO THE PIERCE-ARROW MOTOR CAR COMPANY, OF BUFFALO, NEW YORK, A CORPORATION OF NEW YORK

DESIGN FOR A COMBINED FENDER AND TAIL-LAMP CASING FOR VEHICLES

Application filed September 11, 1929. Serial No. 32,723. Term of patent 14 years.

To all whom it may concern:

Be it known that I, JAMES R. HUGHES, a citizen of the United States of America, and resident of South Bend, in the county of St. Joseph and State of Indiana, have invented a new, original, and ornamental Design for a Combined Fender and Tail-Lamp Casing for Vehicles, of which the following is a specification, reference being made to the accompanying drawing, forming a part thereof.

In the drawing, Figure 1 is a side elevation

and Figure 2 is a rear elevation of the combined fender and tail lamp casing showing my new design.

I claim:

The ornamental design for a combined fender and tail lamp casing for vehicles substantially as shown.

Signed by me at South Bend, Indiana, this 6th day of September, 1929.

JAMES R. HUGHES.
